FLOATING CHAIR FOR SWIMMING POOLS

James F. Denyer, Van Nuys, Calif.

Application July 10, 1959, Serial No. 56,725

Term of patent 7 years

(Cl. D71—1)

Fig. 1.

Fig. 2.

Fig. 4.

Fig. 3.

Fig. 6.

Fig. 5.

Fig. 1 is a perspective view of the floating chair for swimming pools showing my new design;

Fig. 2 is a side elevation thereof;

Fig. 3 is a front elevation thereof;

Fig. 4 is a rear elevation thereof;

Fig. 5 is a top plan view thereof; and,

Fig. 6 is a bottom plan view thereof.

I claim:

The ornamental design for a floating chair for swimming pools, substantially as shown.
